CLAIM

The ornamental design for an underwear, as shown and described.

DESCRIPTION

FIG. 1 is a front perspective view of an underwear showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front perspective view of an underwear of FIGS. 1-7 shown attached to a shirt;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The even-length broken lines in FIGS. 1-12 and 14 represent stitching that forms no part of the claimed design. The dot-dash broken lines in FIGS. 8-14 depict the environment of a shirt that forms no part of the claimed design.

1 Claim, 14 Drawing Sheets
